CLAIM

The ornamental design for a display screen or portion thereof with a graphical user interface having a transitional icon, as shown and described.

DESCRIPTION

FIG. 1 is a front view of a display screen or portion thereof with a graphical user interface having a transitional icon, showing our new design in accordance with a first embodiment and, in particular, showing a first image thereof.

FIG. 2 is a front view of a display screen or portion thereof with a graphical user interface having a transitional icon, showing our new design in accordance with the first embodiment and, in particular, showing a second image thereof.

FIG. 3 is a front view of a display screen or portion thereof with a graphical user interface having a transitional icon, showing our new design in accordance with the first embodiment and, in particular, showing a third image thereof.

FIG. 4 is a front view of the display screen or portion thereof with a graphical user interface having a transitional icon, showing our new design in accordance with the first embodiment and, in particular, showing a fourth image thereof.

FIG. 5 is a front view of the display screen or portion thereof with a graphical user interface having a transitional icon, showing our new design in accordance with the first embodiment and, in particular, showing a fifth image thereof.

FIG. 6 is a front view of the display screen or portion thereof with a graphical user interface having a transitional icon, showing our new design in accordance with the first embodiment and, in particular, showing a sixth image thereof.

FIG. 7 is a front view of the display screen or portion thereof with a graphical user interface having a transitional icon, showing our new design in accordance with the first embodiment and, in particular, showing a seventh image thereof.

FIG. 8 is a front view of the display screen or portion thereof with a graphical user interface having a transitional icon, showing our new design in accordance with the first embodiment and, in particular, showing an eighth image thereof.

FIG. 9 is a front view of the display screen or portion thereof with a graphical user interface having a transitional icon, showing our new design in accordance with the first embodiment and, in particular, showing a ninth image thereof.

FIG. 10 is a front view of the display screen or portion thereof with a graphical user interface having a transitional icon, showing our new design in accordance with the first embodiment and, in particular, showing a tenth image thereof.

FIG. 11 is a front view of the display screen or portion thereof with a graphical user interface having a transitional icon, showing our new design in accordance with the first embodiment and, in particular, showing an eleventh image thereof.

FIG. 12 is a front view of the display screen or portion thereof with a graphical user interface having a transitional icon, showing our new design in accordance with the first embodiment and, in particular, showing a twelfth image thereof.

FIG. 13 is a front view of a display screen or portion thereof with a graphical user interface having a transitional icon, showing our new design in accordance with a second embodiment and, in particular, showing a first image thereof.

FIG. 14 is a front view of a display screen or portion thereof with a graphical user interface having a transitional icon,

showing our new design in accordance with the second embodiment and, in particular, showing a second image thereof.

FIG. 15 is a front view of a display screen or portion thereof with a graphical user interface having a transitional icon, showing our new design in accordance with the second embodiment and, in particular, showing a third image thereof.

FIG. 16 is a front view of the display screen or portion thereof with a graphical user interface having a transitional icon, showing our new design in accordance with the second embodiment and, in particular, showing a fourth image thereof.

FIG. 17 is a front view of the display screen or portion thereof with a graphical user interface having a transitional icon, showing our new design in accordance with the second embodiment and, in particular, showing a fifth image thereof.

FIG. 18 is a front view of the display screen or portion thereof with a graphical user interface having a transitional icon, showing our new design in accordance with the second embodiment and, in particular, showing a sixth image thereof.

FIG. 19 is a front view of the display screen or portion thereof with a graphical user interface having a transitional icon, showing our new design in accordance with the second embodiment and, in particular, showing a seventh image thereof.

FIG. 20 is a front view of the display screen or portion thereof with a graphical user interface having a transitional icon, showing our new design in accordance with the second embodiment and, in particular, showing an eighth image thereof.

FIG. 21 is a front view of the display screen or portion thereof with a graphical user interface having a transitional icon, showing our new design in accordance with the second embodiment and, in particular, showing a ninth image thereof.

FIG. 22 is a front view of the display screen or portion thereof with a graphical user interface having a transitional icon, showing our new design in accordance with the second embodiment and, in particular, showing a tenth image thereof.

FIG. 23 is a front view of the display screen or portion thereof with a graphical user interface having a transitional icon, showing our new design in accordance with the second embodiment and, in particular, showing an eleventh image thereof; and,

FIG. 24 is a front view of the display screen or portion thereof with a graphical user interface having a transitional icon, showing our new design in accordance with the second embodiment and, in particular, showing a twelfth image thereof.

The outermost set of broken lines illustrate an electronic device, the broken line at the periphery of the figures illustrate the display screen, and the remainder of the broken lines illustrate portions of the graphical user interface having a transitional icon. None of the broken lines form part of the claimed design.

The appearance of the first embodiment of the graphical user interface with the transitional icon sequentially transitions among the images shown in FIGS. 1-12. The appearance of the second embodiment of the graphical user interface with the transitional icon sequentially transitions among the

images shown in FIGS. 13-24. The process or period in which one image transitions to another image forms no part of the claimed design.
